(57) **CLAIM**

The ornamental design for camera support bracket, as shown and described.

DESCRIPTION

FIG. 1 is a perspective view of a camera support bracket showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right elevational view thereof;

FIG. 7 is a left elevational view thereof; and,

FIG. 8 is a perspective view thereof in a folded position.

The broken lines in the drawing depict unclaimed environmental subject matter.
